UNITED STATES PATENT OFFICE.

OLOF A. IVERSEN AND HANS A. FINSRUD, OF CHICAGO, ILLINOIS.

SNAP-BUTTON.

No. 847,253.

Specification of Letters Patent.

Patented March 12, 1907.

Application filed September 28, 1906. Serial No. 336,643.

To all whom it may concern:

Be it known that we, OLOF A. IVERSEN, a citizen of the United States, and HANS A. FINSRUD, a subject of the King of Norway, both residents of Chicago, in the county of Cook and State of Illinois, have invented certain new and useful Improvements in Snap-Buttons, of which the following is a specification.

The button of the present invention is intended for use with gloves, suspenders, garters, hand-bags, or similar articles of wearing-apparel in which a snap-button of small size is desirable; and the object of the present invention is to so construct the button and socket members of the device that when one is inserted into the other and turned it will be impossible to disengage the parts from one another by mere tension, but will be necessary to first compress the button member and then turn it a partial revolution in order to disengage the button from the socket. This renders the device peculiarly suitable for securing hand-bags or purses against robbery and securing any articles which are ordinarily subjected to a considerable strain or tension, which often tends to disengage a snap-button of the ordinary type.

The invention consists in the features of construction and combination of parts hereinafter described and claimed.

In the drawings, in which the members are shown greatly enlarged, Figure 1 is a sectional view showing the button-shank inserted into the socket; Fig. 2, a similar view showing the button compressed to allow of disengagement; Fig. 3, a sectional view taken at right angles to the section of Fig. 1, showing the shank in position to be removed from the socket; Fig. 4, a sectional view showing the members disengaged one from the other; Fig. 5, a face view of the socket; and Figs. 6, 7, and 8, fragmentary details of the stud, showing the method of securing the pin therein.

In the drawings, 9 indicates the button member, and 10 the socket member, which members are secured to sections of fabric or leather 11 and 12, respectively. The button member comprises a round head 13, milled around its edge 14, and a stud 15, which inwardly projects from the center of the head. The stud passes through and is embraced by a bow-shaped flat spring 16, which bears against the inner face of the head, and the stud has secured within its inner end a cross-

pin 17. The cross-pin lies within a groove or recess 18 in the end of the stud, and after the pin has been laid in place the walls of the recess are upset, as shown in Fig. 7, to form inwardly-projecting tongues 19, which are embedded within a transversely-extending groove or cut 20 in the center of the pin 18. This arrangement holds the pin firmly and rigidly in place and prevents its displacement. The stud passes through inner and outer washers 21 and 22, respectively, between which the fabric 11 is clamped, and one of the washers is preferably provided with a neck 23, which passes through the fabric and the companion washer and has its rim 25 upset into an annular groove or recess 26 in the companion washer. This arrangement provides a bearing for the stud and at the same time serves to more firmly hold together the two washers and clamp the fabric between them.

The socket comprises a body portion 27, having on its inner or engaging end an enlarged disk-shaped head 28, provided in its center with a circular hole 29 of a suitable size to permit easy insertion of the stud, and the hole on opposite sides merges into key-hole-slots 30, as best shown in Fig. 5. Within the body of the socket is a circular chamber or recess 31, having a diameter substantially equal to the distance from end to end of the keyhole-slots, which arrangement provides an overhanging wall 32 around the major portion of the central hole 29. At right angles to the slots 30 and on the inner face of the overhanging walls 32 are formed a pair of recesses 33 for the reception of the ends of the cross-pin 18 after the stud has been inserted into the socket. The body 27 is provided with a neck 34, which is passed through a washer 35 and has its edge or lip 36 upset into an annular groove or recess 37, which surrounds the opening in the washer.

In use when it is desirable to insert the shank of the button member into the socket the cross-pin on the shank is turned into a proper position to enter the keyhole-slots 30, permitting the stud to be entered into the central hole 29. (Best shown in Fig. 3.) When in this position, the bow-spring will be uncompressed, but by pressing the button-head 14 against the tension of the spring the stud may be inserted to a sufficient degree to bring the cross-pin in line with the circular recess or chamber 31 and in position to permit the button to be turned at right angles to

the initial position to the point indicated in Fig. 2. This turning will bring the pin in line with the undercut recesses 33 in the overhanging walls 32, after which by relieving 5 the pressure on the button-head the stud will be retracted by the tension of the spring, thereby holding the ends of the pin within the recesses provided for their reception. When the parts are thus engaged, it will be 10 impossible to disengage them without performing the operations of initially compressing the button, then turning the button and afterward retracting the button over the socket. At the same time the operation is 15 one which can be very easily performed, in view of the fact that the compressing and turning of the button will constitute practically a continuous operation. No amount of tension, however, will serve to disengage 20 the parts, and this fact renders the button highly superior to the snap-button ordinarily used on gloves, which can be disengaged by a pull or tension and which after continuous usage for a short time becomes 25 so loose and worn that the parts will become disengaged on the slightest provocation. The button of the present invention, moreover, is one which presents a very neat and attractive appearance, the only parts ordinarily exposed being the milled head and the 30 face of the socket-disk.

The principal parts of the button can be made out of gold or silver, if desired, or can be decorated with pearl or gems, so that the 35 button as a whole is one which will be found highly satisfactory for the purposes intended.

The inner and outer washers not only serve to provide a recess for the manipulation of the stud, but also serve to clamp the 40 fabric tightly between the washers, which prevents tearing or displacement of the fabric. The same is true with respect to the disk-shaped head of the socket, which, in combination with the washer 35, serves to 45 clamp the companion section of fabric and prevent tearing or displacement.

The mode of securing applicants' button and socket to the fabric enables the parts to

be made strongly and delicately and at the same time insures sufficient rigidity and 50 strength to permit the button to be used with small articles of wearing-apparel, which is a matter of great importance in the art to which the present invention relates.

What we regard as new, and desire to secure by Letters Patent, is—

In a button of the class described, in combination with two companion sections of material, a stud adapted to outwardly project from one of the sections, an enlarged 60 flat head on the stud adapted to be manipulated by the thumb and finger, a mounting for the stud comprising inner and outer washers on the opposite sides of the section through which the stud is passed, a spring 65 between the head of the stud and the outer washer for normally holding the head and stud retracted, a transversely - extending pin in the end of the stud, a socket secured to the companion section of material and 70 comprising an enlarged disk-shaped head adapted to abut against one side of the material, a body of less diameter than the disk-shaped head and passing through the material, a neck outwardly projecting beyond the 75 body, a washer surrounding the neck and secured thereto and adapted to abut against the material and clamp the material between said washer and the disk-shaped head, the socket being provided with a circular hole 80 of suitable diameter to permit the rotation of the cross-pin, said hole being provided with overhanging walls having therein a key-hole-slot, and the overhanging walls being further provided on their under face with 85 recesses in transverse relation with respect to the keyhole-slot and of a size to receive the cross-pin when entered through the keyhole-slot and turned into transverse relation thereto, substantially as described.

OLOF A. IVERSEN.
HANS A. FINSRUD.
